US0D1097033S

(12) **United States Design Patent** (10) **Patent No.:** **US D1,097,033 S**
(45) **Date of Patent:** **** Oct. 7, 2025**

(54) **BALANCE STEPPING STONE FOR KIDS**

(71) Applicant: **Liyou Industrial Co., Ltd.**, Wenzhou (CN)

(72) Inventor: **Chuci Wu**, Wenzhou (CN)

(73) Assignee: **Liyou Industrial Co., Ltd.**, Wenzhou (CN)

(**) Term: **15 Years**

(21) Appl. No.: **29/916,288**

(22) Filed: **Nov. 9, 2023**

(30) **Foreign Application Priority Data**

Jun. 21, 2023 (CN) 202330385079.4

(51) **LOC (15) Cl.** **21-03**

(52) **U.S. Cl.**

USPC **D21/814**; D21/826

(58) **Field of Classification Search**

USPC D21/598, 671, 811, 814, 826, 827, 832
CPC A63B 2208/12; A63B 26/003; A63B 2026/006; A63B 2071/0655; A63B 2071/0072; A47D 13/04

See application file for complete search history.

(57) **CLAIM**

The ornamental design for a balance stepping stone for kids, as shown and described.

DESCRIPTION

FIG. 1 is a top perspective view of a balance stepping stone for kids showing my present design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a bottom perspective view thereof.

1 Claim, 8 Drawing Sheets
